UNITED STATES PATENT OFFICE.

FRANK P. D'ARCY, OF KALAMAZOO, MICHIGAN.

SIGNAL DEVICE.

1,285,064.

Specification of Letters Patent. Patented Nov. 19, 1918.

Application filed July 24, 1917. Serial No. 182,480.

To all whom it may concern:

Be it known that I, FRANK P. D'ARCY, a citizen of the United States, residing in the city and county of Kalamazoo, State of Michigan, have invented certain new and useful Improvements in Signal Devices, of which the following is a specification.

This invention relates to improvements in signal devices.

10 The main object of the invention is to provide a signal device especially adapted for the use of traffic guards or police, which is simple in structure, economical to manufacture and easy to manipulate.

15 Further objects, and objects relating to structural details, will definitely appear from the detailed description to follow.

I accomplish the objects of my invention by the devices and means described in the 20 following specification. The invention is clearly defined and pointed out in the claims.

A structure which is a preferred embodiment of my invention is clearly illustrated in the accompanying drawing, forming a 25 part of this specification, in which:

Figure I is a side elevation of my improved signal in an upright position.

Fig. II is a similar view in inverted position.

30 Fig. III is a sectional detail taken on a line corresponding to line 3—3 of Fig. I.

Fig. IV is an enlarged sectional detail taken on a line corresponding to line 4—4 of Fig. I.

35 Fig. V is a side elevation of another embodiment of my invention in upright position.

Fig. VI is a similar view of the embodiment of Fig. V in inverted position.

40 Fig. VII is a sectional detail taken on a line corresponding to line 7—7 of Fig. V, portions of the signal being broken away.

Fig. VIII is an enlarged detail section taken on a line corresponding to line 8—8 of 45 Figs. V and VI.

Figs. IX and X illustrate an embodiment of my invention as shown in Figs. I and II, in which the indicia is disposed entirely upon the signal plate.

50 Figs. XI and XII illustrate an embodiment of my invention in which complete indicia is provided upon the signal and upon the cover plates.

In the drawing similar reference characters refer to similar parts throughout the several views, and the sectional views are

taken looking in the direction of the little arrows at the ends of the section lines.

Referring to the drawing, the reference character 1 indicates the signal plate which, in the preferred embodiment of my invention, is a disk of sheet metal. On a diameter of this disk, I displace the metal of the disk to form aligned alternate oppositely disposed channels 2 and 3 respectively. These 60 channels receive the pintle eyes 4 and 5 respectively of the cover plates 6 and 7. The signal plate 1 is provided with a handle 8 which is illustrated as extending at right angles to the direction of the hinge pintle 9 which passes through the pintle eyes 4 and 5, but it is to be understood that this handle may be attached to the signal plate 1 in other positions. The ends of the hinge pintle 9 are bent over, as indicated at 10, to prevent it from displacement.

70 The signal plate 1 is provided with signal indicia on opposite sides of the pivot line of the cover plates 6 and 7 in inverted relation. In Figs. I and II these indicia are illustrated as comprising the top half of the words "Stop" and "Go." The cover plates 6 and 7 are provided with indicia complementary to the indicia on the adjacent portions of the signal plate, and these indicia, 75 as illustrated, comprise the lower half of the words "Stop" and "Go."

With the above structure, when the signal is held in an upright position, as shown in Fig. I, the cover plates drop to the position shown therein and in Fig. III, and the complementary indicia upon the signal plate and cover plate form the word "Stop" on each side of the signal, but when the signal is inverted, as shown in Fig. II, the cover plates turn about their pivot and drop to the top of the signal plates, and the complementary indicia upon the signal plates and the cover plates form the word "Go."

80 In the modified embodiment of my invention shown in Figs. V to VIII, I provide a signal plate 1' to which is secured upon opposite sides of each edge thereof, the channel-shaped slide-way members 11 which receive the edges of the cover plates 12. A 85 handle 13 secured to one end of the signal plate provides stops 14 for limiting the movement of the cover plates in one direction and oppositely disposed lugs 15, formed at the other end of the cover plate, provide 90 stops for limiting the movement of the cover plate in the opposite direction. The signal 95

100

105

110

plate 1' is provided on both sides at opposite ends thereof with indicia in inverted relation, the said indicia being illustrated as comprising the words "Stop" and "Go."

- 5 When the signal is held in an upright position, as shown in Fig. V, the cover plates 12 drop to the bottom of the signal plate 1' and uncover the word "Stop" on both sides of the upper end of the signal plate. When
- 10 the signal plate is held in inverted position, the cover plates drop to the top of the signal plate and cover the word "Stop" and exposes the word "Go."

In Figs. IX and X I illustrate an adaptation of my invention in which the indicia is entirely upon the signal plate. In Figs. XI and XII I illustrate an adaptation of my invention in which both the signal and the cover plates are provided with complete in-

20 dicia.

My improved signal device is very convenient to use, as it is only necessary for the traffic guard or policeman to raise the signal or drop the same and, as the raising 25 of a signal or hand is commonly understood to indicate a stop, the signal is understood, even from such distance as prevents the reading of the indicia, or by persons whose eyesight is such as prevents reading from a 30 distance.

Having thus described my invention, what I claim as new and desire to secure by Letters Patent, is:

1. In a signal device, the combination of 35 a signal plate provided with a handle and having aligned alternately disposed channels therein providing pintle eyes, cover plates provided with pintle eyes disposed in said channels, and a pintle for said cover plates,
- 40 said signal plate having upon each side two sets of indicia disposed in inverted relation on opposite sides of its said pintle bars, said cover plates having on their opposite sides indicia complementary to the indicia on the 45 adjacent portions of the signal plate.

2. In a signal device, the combination of

a signal plate provided with a handle, cover plates pivoted on said signal plate, said signal plate having upon each side two sets of indicia disposed in inverted relation, said 50 cover plates having on their opposite sides indicia complementary to the indicia on the adjacent portions of the signal plate.

3. In a signal device, the combination of a signal plate provided with a handle and 55 having aligned alternately disposed channels therein providing pintle eyes, cover plates provided with pintle eyes disposed in said channels, and a pintle for said cover plates, said signal device having indicia which is 60 alternately covered and uncovered by the shifting of said cover plates, the cover plates being automatically shifted by the changing of said signal device from its upright to its inverted position and vice versa. 65

4. In a signal device, the combination of a signal plate provided with a handle, pivoted cover plates, said signal device having indicia which is alternately covered and uncovered by the shifting of said cover plates, 70 the cover plates being automatically shifted by the changing of said signal device from its upright to its inverted position and vice versa.

5. In a signal device, the combination of 75 a signal plate having two sets of indicia on one side thereof in inverted relation, and means for covering one set of indicia and uncovering the other set when the said signal plate is held in one position and for covering the indicia on the opposite end of said 80 plate and uncovering the other set of indicia when the said plate is held in an inverted position.

In witness whereof, I have hereunto set 85 my hand and seal in the presence of two witnesses.

FRANK P. D'ARCY. [L. S.]
